UNITED STATES PATENT OFFICE.

LEONARD S. BALUTA, OF BERWICK, PENNSYLVANIA.

SHOE ATTACHMENT.

Application filed April 27, 1921. Serial No. 464,970.

To all whom it may concern:

Be it known that I, LEONARD S. BALUTA, a citizen of the United States, residing at Berwick, in the county of Columbia and 5 State of Pennsylvania, have invented certain new and useful Improvements in Shoe Attachments, of which the following is a specification.

This invention relates to improvements in 10 shoes, and the primary object of the invention is to provide a novel device carried by the shoe for facilitating the positioning of the shoe of the low quarter type on the foot, which will eliminate the use of any 15 extraneous object, such as a shoe horn for this purpose.

Another object of the invention is to provide a shoe attachment embodying a flexible 20 guide carried by the rear end of the shoe or slipper for guiding the foot into the shoe or slipper, the flexible guide being so formed and associated with the shoe in such a manner as to form a cushion for the heel of the wearer of the shoe and a protector for 25 the quarter of the shoe, the guide eliminating or taking the place of the ordinary back stay of the shoe.

A further object of the invention is to 30 provide a guide for shoes of the low quarter type, for facilitating the placing of the shoes on the foot, which embodies means for engaging a rubber or overshoe, when worn, so as to prevent the slipping or riding up and down of the heel of the over- 35 shoe on the shoe.

A still further object of the invention is 40 to provide an improved guide for facilitating the placing of the shoe on the foot, which is so constructed as to add to rather than detract from the appearance of the shoe, and which can be incorporated with ordinary types of shoes, without changing the mode of manufacture thereof, and without adding to the cost of manufacture 45 thereof.

With these and other objects in view the invention consists in the novel construction, arrangement and formation of parts, as will be hereinafter more specifically 50 described, claimed and illustrated in the accompanying drawings, forming a part of this specification, in which drawings:

Figure 1 is a perspective view of a shoe 55 with the improved guide attached thereto, the guide being in its extended position for

facilitating the placing of the shoe on the foot.

Figure 2 is a rear elevation of a shoe with the guide incorporated therewith, showing the guide in its inoperative normal position. 60

Figure 3 is a fragmentary longitudinal section through the shoe and attachment taken on the line 3-3 of Figure 2.

Figure 4 is a view similar to Figure 3, showing the attachment used for holding an 65 overshoe in place against movement.

Referring to the drawings in detail, wherein similar reference characters designate corresponding parts throughout the several views, the letter A indicates a shoe; 70 B, the improved attachment therefor; and C an overshoe.

The shoe A may be of any preferred type or character, and as shown is of the low quarter or oxford type, and embodies the 75 sole 5, the insole 5', the heel 6, the vamp 7, and the quarter 8.

The attachment B takes the place of the usual back stay and is adapted to be folded over the back of the quarter as clearly 80 shown in Figure 2 of the drawings, and the attachment B adds to the appearance of the shoe.

The attachment B can be formed of any 85 flexible material but preferably of leather of a suitable color to harmonize with the shoe with which it is associated. As shown the attachment B includes a body 10 which extends into the interior of the quarter of the shoe at the rear end thereof, and extends 90 up from the inner sole of the shoe, the inner end of the body is held in place by fastening rivets 13 or in any preferred manner. The inner end of the body 10 can be placed between the insole 5' and the heel 6 if so 95 desired. As shown the shank 11 of the resilient head 12 of the ball and socket fastener 13 is utilized for holding the same in place. The body 10 is adapted to extend above the shoe for a considerable distance 100 to form a tab or pull 14 and when the attachment is not in use, the tab 14 is adapted to be folded over the rear end of the quarter and is shaped similar to the ordinary back stay and is adapted to take the place of the ordinary back stay. The extreme outer end of the tab 14 carries the resilient socket 15 105 which forms a part of the socket fastener 13, and this socket is adapted to engage the head 12, which holds the tab in position.

100

105

110

The means of associating the body 10 with the shoe does not form any bulky or cumbersome attachment, and the same is hardly noticeable on the shoe.

5 If so desired the outer surface of the head 15 of the ball and socket fastener 13 may be engraved or impressed with the owner's initial or with a suitable fraternal emblem or the like.

10 The body portion 10 of the attachment which is positioned within the shoe forms a cushioning for the heel of the foot and prevents the rubbing of the heel by the shoe and prevents the riding up and down of the 15 shoe on the heel of the wearer.

In use of the improved attachment, the socket 15 is removed from the head 12 and the tab 14 is raised to its extended position as shown in Figure 1 of the drawings and 20 held in this position by the hand of the user as is very clearly shown in Figure 1 of the drawings. The shoe is placed on the foot in the ordinary manner, and the body will form a guide for the heel of the foot 25 and direct the same into the shoe. The attachment also forms a means for pulling the shoe on the foot as is readily apparent. The tab 14 being arranged on the outer surface of the shoe at the rear end thereof forms a 30 wear member for the shoe and prevents the same from becoming scarred and the like.

As stated in the objects of the specification, the attachment can be conveniently used for holding overshoes or rubbers in position 35 on the shoe for preventing the overshoe from riding up and down on the heel portion of the shoe. In this instance, the overshoe which is designated by the letter C can be provided with a resilient head 16 and the 40 tab portion 14 of the attachment B is adapted to be placed over the outer surface of the heel portion of the rubber and the socket 15 snapped over the head 16. Thus it can be seen that the overshoe will effectively be 45 held in position.

To prevent wear on the inner surface of the overshoe by the resilient head 12 of the ball and socket fastener 13, a guard plate 17 which can be formed of metal or the like 50 is secured to the inner face of the heel portion of the overshoe. If so desired this plate 17 can form a portion of the shank of the resilient head 16 carried by the overshoe.

When overshoes are worn, of the type 55 which merely include a sole and a heel strap, the tab 14 is placed around the strap and the socket 15 is placed over the resilient head 12. It thus can be seen that the tab will engage the strap and prevent the same from riding out of engagement with the rear portion 60 of the heel of the shoe.

From the foregoing description, it can be seen that an exceptionally simple and durable attachment has been provided for shoes 65 of the low quarter type, which will not only

facilitate the positioning of the shoe on the foot, but will also act as a guard for the rear end of the shoe as a cushion for the heel of the foot of the wearer of the shoe and as a means for holding overshoes on the 70 shoe.

Changes in details may be made without departing from the spirit or scope of this invention; but,

I claim:

1. The combination with a shoe, of a guide therefor including a body secured at its lower end to the inner surface of the heel portion of the shoe and having its side edges free and a tab arranged to extend exteriorly of the shoe.

2. The combination with a shoe, of a guide attachment therefor for facilitating the position of the shoe on the foot of a wearer including a flexible body secured at 85 its inner end to the inner surface of the heel portion of the shoe and having its side edges free to permit swinging movement of the guide attachment.

3. The combination with a shoe, of a guide attachment therefor for facilitating the positioning of the shoe on the foot of a wearer including a flexible body and a tab, and means securing the lower end of the flexible body to the inner surface of the 95 heel portion of the shoe at the rear end thereof the side edges of the body being free to permit swinging movement of the body.

4. The combination with a shoe, of a guide attachment, therefor comprising a 100 flexible body and a tab, means for securing the body to the inner surface of the shoe, and means for detachably securing the tab to the outer surface of the shoe the side edges of the body being free to permit 105 swinging movement of the body.

5. The combination with a shoe, of an attachment therefor including a flexible body, secured at its inner end to the inner heel portion of the shoe, the side edges of the shoe being left free to permit swinging movement of the body, a tab arranged to extend exteriorly of the shoe, a resilient head carried by the outer surface of the shoe including 110 an attaching shank portion, the shank portion engaging the flexible body to hold the same in position on the inner surface of the shoe, and a socket member carried by the outer end of the tab for engaging the resilient head.

6. The combination with a shoe and an overshoe, of an attachment for the shoe and overshoe including a flexible body secured at its lower end to the inner surface of the shoe, the side edges of the body being left free to permit swinging movement of the body, and a flexible tab arranged to extend exteriorly of the shoe, a resilient head carried by the outer surface of the shoe, a resilient head carried by the outer surface of the 125 overshoe, the tab being arranged to engage the resilient head.

overshoe, and a socket carried by the tab arranged to engage the resilient head carried by the shoe when the overshoe is not in place or the resilient head carried by the overshoe when the same is in place on the shoe.

7. The combination with a shoe, of an attachment therefor including a flexible body, means securing the inner end portion of the body to the inner surface of the heel portion

of the shoe with the inner end of the body extending between the heel and insole of said shoe and the sides of the body free; a tab arranged to extend exteriorly of the shoe and being of such a length as to form 15 the back stay for the shoe, and means for detachably securing the outer end of the tab in a turned down position.

LEONARD S. BALUTA.
